SPECIFICATION forming part of Design No. 23,989, dated February 5, 1895.
Application filed September 8, 1894. Serial No. 522,505. Term of patent 3½ years.

To all whom it may concern:

Be it known that I, ARTHUR DANBY, a citizen of the United States, residing at Philadelphia, in the State of Pennsylvania, have invented and produced a certain new and original Design for a Carpet Fabric, of which the following is a full, clear, and exact description, reference being had to the accompanying drawing, forming a part of this specification.

My invention relates to the surface ornamentation of Wilton and other carpet fabrics, and consists of the design therefor shown in the accompanying drawing.

15 The unitary figure presents the appearance of a nearly round panel-pattern, and is com-

posed of leaf-like figures *a* joined to each other at their several bases or ends to form an open field center; and inclosed therein, as a center figure, is a bouquet *b* of leaves and buds.

I claim—

The design for a carpet fabric substantially as shown and described.

In testimony whereof I have hereunto affixed my signature this 31st day of August, A. D. 1894.
